UNITED STATES PATENT OFFICE.

LEWIS L. NETTLETON, OF EDGEWOOD BOROUGH, AND LARS O. GRONDAHL, OF PITTSBURGH, PENNSYLVANIA, ASSIGNEES TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 22, 1926. Serial No. 143,379.

Our invention relates to railway traffic controlling apparatus, and particularly to apparatus of the type wherein alternating current is periodically supplied to the track rails for the control of traffic governing mechanism which is responsive to such periodic supply of alternating current but not to the continuous supply of such current.

One form of apparatus of the character referred to is disclosed and claimed in application for Letters Patent of the United States filed by C. S. Snavely on May 29, 1926, Serial No. 112,491. In the apparatus disclosed in that application, when a section is occupied by a train and the next section in advance is unoccupied, alternating currents of two different frequencies are alternately applied to the track rails, and the train-carried apparatus is tuned to respond to one of these currents but not the other. This tuning is usually accomplished by an electric filter, but we have found that under some conditions the filter may respond to what we term "shock excitation", that is, when an alternating current is suddenly applied at its full value to the track rails, the filter receives an impulse which causes it to oscillate and so to falsely apply voltage to the train-carried apparatus, and this may be true even though the current which is abruptly applied is the current to which the filter is not tuned.

One feature of our invention is the provision of means for preventing sudden application of current to the track rails, that is, means for lowering the rate of increase of the current to its full value when the current is applied.

We will describe one form of apparatus embodying our invention, and will then point out the novel features thereof in claims.

The accompanying drawing is a diagrammatic view showing one form of apparatus embodying our invention.

Referring to the drawing, the reference characters 1 and 1^a designate the track rails of a railway along which traffic normally moves in the direction indicated by the arrow. These rails are divided into track sections of which only one section C—D is shown in the drawing. Located at the exit end of section C—D are two transformers E⁶⁰ and E¹⁰⁰, the secondaries 11 and 9 of

which are connected in series across the rails 1 and 1^a. The primary 10 of transformer E⁶⁰ is at times supplied with alternating signaling current from the secondary 12 of a transformer T⁶⁰, the primary 13 of which is constantly connected with a source of alternating current which is not shown in the drawing. Similarly, the primary 8 of transformer E¹⁰⁰ is at times supplied with alternating current from the secondary 14 of a transformer T¹⁰⁰, the primary 15 of which is constantly connected with a source of alternating current not shown in the drawing. The currents supplied to the transformers T differ in frequency, and, as an example, the current supplied to transformer T⁶⁰ may be 60 cycles per second, and the current supplied to transformer T¹⁰⁰ may be 100 cycles per second.

The supply of current to the transformers E is controlled by a relay G, which we will term a "coding" relay, and this relay is in turn controlled by a track relay F which is connected across the rails at the entrance end of section C—D and is responsive to the 60 cycle current supplied to these rails by transformer E⁶⁰. The coding relay G is provided with a circuit which passes from terminal B of a suitable source of current through back contact 3 of track relay F, winding of relay G, and back contact 4 of relay G to terminal O of the same source of current. It will be seen, therefore, that when section C—D is unoccupied and track relay F is energized, relay G will be at rest in its de-energized condition, but that when track relay F is de-energized the coding relay G will be alternately energized and de-energized, due to the fact that its back contact 4 is included in the circuit for this winding.

The reference character H⁶⁰ designates a thermo-sensitive relay having a heating element 6 and a thermo-sensitive element 7. The thermo-sensitive element 7 is included in the primary circuit for transformer E⁶⁰. The reference character H¹⁰⁰ designates a similar thermo-sensitive relay, the thermo-sensitive element 7 of which is included in the primary circuit for transformer E¹⁰⁰. The heating element 6 of relay H⁶⁰ is provided with a circuit which includes a battery 16 and a back contact 5 of the coding relay G; the heating element 6 of relay H¹⁰⁰ is pro-

vided with a similar circuit, which includes the battery 16 and the front contact 5 of coding relay G.

The parts are so adjusted that when the heating element 6 of either relay H is de-energized, the thermo-sensitive element 7 is of such high resistance that substantially no current is supplied to the primary of the associated transformer E, whereas, when the heating element 6 of either relay H is energized, the resistance of the thermo-sensitive element 7 of such relay is reduced to such value that current of an operating value is supplied to the associated transformer E.

15 Normally when the section C—D is un-occupied, so that coding relay G is at rest, the heating element 6 of relay H⁶⁰ is en-ergized so that 60 cycle current is supplied to transformer E⁶⁰, and this current in the 20 track rails of section C—D holds the track relay F in its energized condition. When a train enters section C—D, however, the opening of relay F causes periodic opera-25 tion of the coding relay G, so that the heating elements 6 of the relays H⁶⁰ and H¹⁰⁰ are alternately energized, with the result that 60 cycle current and 100 cycle current are alternately supplied to the track rails through the transformers E⁶⁰ and E¹⁰⁰, re-30 spectively. Each time that the front or the back contact of the coding relay G closes, the heating element of one of the relays H becomes energized; but a time interval is required for the thermo-sensitive element 35 of such relay to become heated to its ultimate temperature; and, consequently, a time interval is required for the alternating current supplied through such relay to build up to its ultimate value. This time inter-40 val may, for example, be the time required for approximately five cycles of 60 cycle current. This slow building up of the current applied to the track rails prevents sud-45 den excitation of the filter or other tuning device which receives current from the track rails; and, consequently, eliminates the transient impulse which is likely to pass through the filter if current is instantaneously applied to the track rails at its full value.

50 Although we have herein shown and de-scribed only one form of apparatus embody-ing our invention, it is understood that vari-ous changes and modifications may be made therein within the scope of the appended 55 claims without departing from the spirit and scope of our invention.

Having thus described our invention, what we claim is:

1. In railway traffic controlling apparatus of the type comprising means for periodically supplying current to the track rails, the combination therewith of means for lowering the rate of increase and decrease of such current in the track rails. 60

2. In railway traffic controlling apparatus of the type comprising means for periodically supplying current to the track rails, the combination therewith of means for causing the current in the track rails to build up slowly each time it is supplied to the 70 rails. 70

3. In railway traffic controlling apparatus of the type comprising means for periodically supplying current to the track rails, the combination therewith of means for lowering the rate of increase of such current in the track rails. 75

4. In railway traffic controlling apparatus of the type comprising means for periodically supplying current to the track rails, the combination therewith of means for preventing sudden increase of the current in the track rails. 80

5. In combination with the track rails of a railway and a source of current connected therewith, means interposed between said source and a track rail for periodically vary-ing the value of the current supplied to the rails and for preventing sudden change in such value. 85

6. In combination with the track rails of a railway, a source of current connected with said rails through a thermo-sensitive substance, a heating element for varying the temperature of said substance, and a circuit for said heating element including a period-ically operating contact. 90

7. In combination with the track rails of a railway, a source of a ternating current of one frequency connected with said rails through a thermo-sensitive substance, a sec-ond source of alternating current of a dif-ferent frequency connected with said rails through a second thermo-sensitive substance, a heating element for each thermo-sensitive substance, and means for alternately supply-ing current to said heating elements. 95 100 105

In testimony whereof we affix our signatures.

LEWIS L. NETTLETON,
LARS O. GRONDAHL.
